UNITED STATES PATENT OFFICE.

CHARLES VERBSKY, OF LAKESIDE, OHIO.

SPECULUM.

1,260,604.

Specification of Letters Patent. Patented Mar. 26, 1918.

Application filed January 11, 1918. Serial No. 211,846.

To all whom it may concern:

Be it known that I, CHARLES VERBSKY, a citizen of the United States, residing at Lakewood, in the county of Cuyahoga and 5 State of Ohio, have invented certain new and useful Improvements in Specula, of which the following is a specification.

This invention relates to specula and especially to specula of the duck bill type, 10 having a pair of articulated blades which are capable of being opened and closed while in use for the desired purposes.

The object of the invention is to provide improved means for adjusting the position 15 or angles of the blades, and to provide a device which can be easily manipulated, and which will accomplish a dilation without danger of slipping and which can be easily operated with either hand, preserving also 20 a wide space at the external opening of the instrument.

A further object of the invention is to provide a convertible speculum which can be converted into an instrument of the one-bladed type, the two blades being locked or 25 fastened together at a suitable angle for the manipulation of the device as one piece.

Other features of novelty or advantage 30 will appear from the following description and the accompanying drawings.

In the drawing Figure 1 is a perspective view of the device. Fig. 2 is a central longitudinal section. Fig. 3 is a cross section. Fig. 4 is a perspective view of the device 35 converted into a single bladed angular instrument.

Referring specifically to the drawings, the device consists of two blades indicated at 6 and 7 the main parts of which are of the 40 ordinary duck bill type. The member 7 I will call the relatively fixed blade and 6 the adjustable blade, the rear end of the former being curved outwardly or flared to a somewhat greater extent than the latter, as indicated at 8, and the blade 6 may be slotted at the rear end as indicated at 9. These two blades are hinged together at their rear ends by means of pins or projections 10 projecting from the ends of a bail 11 which is looped at 45 the arch to form an eye 12. The pins 10 snap or slip into holes at the rear meeting corners of the blades, as shown, and thereby hinge the blades together. A curved screw 13 works loosely through the eye 12, and 50 receives a nut 14 to take up the screw and exert pressure to spread the blades. The

inner end of this screw is hooked as shown at 15, the hook being S shaped, so that its 50 bill may be entered in the notch 16 and a hole 17 at the end of the extended part 8 of the blade 7. This connection permits the screw to be disengaged from the hole quite 60 readily, after the nut 14 is taken off and the bail 11 swung clear of the screw 13. The 65 screw can then be swung out and detached from the blade, but it will stay in place ordinarily. The relatively adjustable blade 6 is provided near its hinged points with outwardly extending shoulders 18, so located 70 that the bail 11 will stop against these 70 shoulders when the pressure of the nut is applied thereto, causing the bail to then act as a lever to swing the blades open, and in use as a duck bill specula the nut may be 75 operated by hand to produce the required expansion or dilation.

For use as a rigid or single bladed instrument the blades are first separated. This is done by taking off the nut 14 and removing the screw 13. Then the legs of the bail are 80 sprung apart to withdraw the hinge pins 10 from the holes in which they fit. This disjoins the blades and they fall apart. Or, the bail may be disconnected first, and then the screw unhooked without taking off the 85 nut 14. After the blades are disjoined they are then reversed, and the rear end of the 90 blade 7 is then lapped or fitted within the rear end of the blade 6. Then, the pins 10 of the bail are slipped into the registering holes 90 in the blades, which are thus fastened together. The curvature or concavity of the rear ends of the blades is substantially the same so that they fit closely one into the other as shown in Fig. 4, and after being 95 hooked together by the bail as shown and described they cannot turn with respect to each other, but form a substantially rigid angular speculum, one blade of which may be used as a handle and the other as a dilator. 100 Fig. 4 shows the instrument in this position, the bail being preferably lodged against the inner or concave side of the handle part.

The instrument is therefore capable of being converted with facility from one type 105 to the other, which will be found very serviceable for operative purposes under different conditions.

The invention is not limited to the special form or arrangement shown, but may be 110 modified in various ways within the scope thereof.

The instrument consists of but five parts which can be readily separated to be cleaned or sterilized.

I claim:

5. 1. A speculum comprising a pair of blades, a bail having hinge pins at its ends, connecting the rear ends of the blades, and an adjusting screw between the bail and one of the blades, said bail being engageable with 10 the other blade to swing the same on the hinge.
2. A speculum comprising a pair of blades, a bail having hinge pins at its ends, connecting the rear ends of the blades, one of 15 the blades having stops to prevent movement of the bail with respect thereto in one direction, and an adjusting screw between the bail and the other blade.
3. A speculum comprising a pair of blades, 20 a bail having hinge pins detachably connecting the rear ends of the blades, and a detachable screw connection between said bail and one of the blades, said bail being engageable with the other blade to swing 25 the same on the hinge.
4. A convertible speculum comprising two

blades, and means to hinge the same together to form a double-bladed speculum, said means being detachable to permit disjointing of the blades, and the rear ends of said blades 30 being shaped to fit together in lapped relation, to form a single-bladed speculum, said means being then engageable to hold the blades together.

5. A speculum comprising two blades convertible to either opposed or lapped relation, to produce either a double bladed or a single bladed instrument, and means to hold the blades together in either of said 35 relations.

6. A speculum comprising two blades the rear ends of which may be hinge-jointed or lap-jointed to each other, to form either a double bladed or single bladed instrument, and means to hold the said ends together, in 40 either relation.

In testimony whereof, I do affix my signature in presence of two witnesses.

CHARLES VERBSKY.
